UNITED STATES PATENT OFFICE.

JESS B. HAWLEY, OF EVANSTON, ILLINOIS, ASSIGNOR TO AMERICAN SEAMLESS CONTAINER COMPANY, OF CHICAGO, ILLINOIS, A CORPORATION OF DELAWARE.

FASTENING DEVICE FOR SHIPPING-CASE COVERS.

1,417,827.

Specification of Letters Patent. Patented May 30, 1922.

Application filed March 11, 1920. Serial No. 364,901.

To all whom it may concern:

Be it known that I, JESS B. HAWLEY, a citizen of the United States, residing at Evanston, in the county of Cook and State 5 of Illinois, have invented certain new and useful Improvements in Fastening Devices for Shipping-Case Covers, of which the following is the specification.

This invention relates to a device for 10 fastening covers to shipping cases, and has for an object the improvement of the general construction of this class of devices, and the provision of a hardware trimming for pails.

15 Among the further objects of this invention is to provide a hoop, bail and fastening loops, all secured together, and ready to be instantly applied as a unit to a pail; further to provide a novel manner of securing the lightning and holding wires to 20 the hoop; further to provide a form of fastening device that adapts itself to the nesting of the pails in one another; further to form a beaded hoop in practically continuous form by welding together the meeting ends of the hoop, the bead forming a 25 pressure receiving surface for forcing the hoop into tightened position on the pail; further to position the bent end of the 30 handle bail between the hoop and pail, so that it will be hidden, and as a result of the friction between the bail end and the side of the pail, the bail will stand in such 35 position as it may occupy at any time; further to conceal and render inaccessible, the free end of the wire fastening loops, in such manner that the loop cannot be removed, and to prevent the formation of 40 short kinks therein; further to provide a form of fastener that cannot be tampered with without detection; further to provide a completely assembled hardware trimming for pails, that can be quickly applied in 45 position to the pail; further to provide a more simple, economical and efficacious device of the class described, and such further objects, advantages and capabilities as will later more fully appear.

My invention further resides in the combination, construction and arrangement of parts illustrated in the accompanying drawings, and while I have shown therein a preferred embodiment, I desire the same to be understood as being merely illustrative,

and not as limiting the scope of my invention.

In the drawings:—

Fig. 1 is a perspective view of a pail and cover, and showing my improved fastening device in position to fasten the cover 60 to the pail.

Fig. 2 is a vertical transverse section through the upper portion of Fig. 1.

Fig. 3 is a perspective view of my unitary hardware trimming for pails, and comprising 65 the hoop, fastening loops and handle bail.

Fig. 4 is a fragmentary vertical sectional view showing the manner of securing the free end of the wire loops to the bail. 70

Fig. 5 is a fragmentary sectional view showing the manner of securing the end of the handle bail to the hoop.

While my invention is particularly adapted and useful in connection with fibrous 75 pulp pails, and I have so illustrated it, I desire it to be understood that the same is capable of application to other forms of pails, as desired.

My improved hardware trimming comprises the hoop 1, adapted to be tightly applied to a pail 2, and to the hoop are secured the free ends of the wire fastening loops 3, and the ends of the handle bail 4. After the hoop has been applied to the pail, 85 the upper ends of the loops 3 will be caused to overlap over the top of the cover, and a suitable instrument, such as a short bar, or the like, passed between the overlapping ends of the loops, and the loops 90 twisted together as shown in Fig. 1.

Referring to Figs. 3 and 4, the free ends of the loops 3 are each secured to the hoop 1, by being passed outwardly through an aperture 5 in the hoop, and thence bent upwardly 95 as shown at 6, and thence over the top edge of the hoop as indicated at 7, and the free end 8 then bent downwardly on the inside of the hoop. Each of the bends referred to are of gradual curvature, and entirely free of 100 any short and abrupt kinks, and when the hoop is pressed into position on the outside of the pail, the inner free end 8 will be secure between the pail and hoop. When the loops are twisted together, the tension therein 105 will be upwardly against the edge of the aperture 5, and the free end 8 being held between the pail and the hoop will furnish

perfect resistance to any danger of the loop being pulled away from the hoop. This construction renders it impossible for anyone to surreptitiously remove the fastening loops 3 from the pail while in transit, without such removal being readily discovered. This latter feature I consider of very great importance and broadly new.

The handle bail 4 is secured to the hoop by passing each of its free ends inwardly through oppositely positioned apertures 10, and the free end portion 11 being bent within the hoop to stand approximately parallel with that portion of the bail outside of the hoop. When the hoop is forced into tight engagement with the pail, the friction between the free end 11 of the bail and the sides of the pail will be sufficient to hold the bail in any position in which it may be left standing.

The hoop 1 is provided on its lower marginal edge with the beaded portion 12, which bead provides a surface to receive pressure for forcing the hoop into tight engagement with the sides of the pail. Such pressure may be applied by the usual rollers used in this class of work, or by any other form of driving means desired. The free ends of the hoop are securely fastened together by welding, as indicated generally at 13, and which weld may be a butt weld or lap weld, electrically or otherwise effected, as desired. This feature of providing beaded hoops, with their free ends welded together, I consider important and new. Or I may if desired secure the ends of the hoop by riveting.

The dotted lines in Fig. 3 show the fastening loops in overlapped position prior to their being twisted together as described above.

It will thus be seen that amongst other features of importance, I have provided a hardware trimming of unitary structure comprising a hoop, wire fastening loops, and a handle bail, completely assembled together in the shop prior to their being applied to the pail. By my invention not only is the efficiency of cover fastening devices greatly increased and perfected, but the manufacturing of the same can be much more rapidly accomplished, in the case of the present invention it being possible for one man to apply fifteen hundred or more of these unitary fastening devices in a nine hour day, and which application of these fastening devices is the last operation performed upon the pail.

It is also to be noted that my improved form of fastening device adapts itself admirably to the nesting together of the pails, it only being necessary in this connection to bend the wires downwardly within the inside of the pail, and seat the next pail therein.

Having now described my invention, I claim:

1. In a device of the class described, a hoop, a plurality of wire loops adapted to be twisted together over the outside of a pail cover, the free ends of said loops being each passed outwardly through an aperture in the hoop, then bent upwardly and inwardly, and the free end portion of the loop being bent downwardly along the inside of the hoop.

2. In a unitary hardware trimming for pails, comprising a hoop adapted to be driven into tight engagement with the sides of a pail, a plurality of wire loops passing through apertures in said hoop and adapted to be twisted together over a pail cover, and a handle bail passing through apertures in said hoop, said hoop, loops, and bail, all formed in a unitary structure prior to application to the pail.

3. In a fastener for a pail, a hoop beaded to provide an annular shoulder to receive pressure for driving the hoop into tightened position on said pail, and means secured to said hoop bearing against the sides of the pail to prevent said hoop from downward movement, said beaded hoop having its ends welded together.

4. In a device of the class described, a hoop adapted to be forced into tight engagement with a pail, a handle bail secured to said hoop, the ends of said bail passing inwardly through apertures in the hoop, then extending substantially parallel with that portion of the bail adjacent the outside of the hoop, whereby when the hoop and bail are applied to a pail the bail will stand in such position as it may be left.

5. In combination, a pail, a hoop encircling the same, a handle bail having its free ends passing inwardly through apertures in the hoop, and then upwardly between the hoop and pail whereby friction between the bail end and the pail will hold the bail wherever placed and prevent said hook from slipping upward when the bail is in carrying position.

6. In combination, a pail, a cover, a hoop encircling the pail, a plurality of wire loops secured to said hoop and adapted to be twisted together over the pail cover, the free ends of the loops passing outwardly through apertures in the hoop, thence curved upwardly and inwardly over the hoop and thence extending downwardly inside the hoop between the hoop and pail, said bent portions being free of short kinks or abrupt bends, whereby to increase the effective strength of the loops.

7. A unitary fastening device for shipping case covers comprising a hoop beaded at its lower edge to provide an annular shoulder, apertures in said hoop, a handle bail having its free ends passing inwardly

through two of said apertures and then bent to extend upwardly between the pail and the hoop when the handle is in the lifting position, and a plurality of wire loops having their free ends passing outwardly through apertures in the hoop, thence curved upwardly and inwardly over the hoop and thence downwardly inside the hoop between the hoop and the pail, said bent portions 10 being free of short kinks or abrupt bends,

whereby to increase the effective strength of the loops.

In witness whereof, I hereunto subscribe my name to this specification in the presence of two witnesses.

JESS B. HAWLEY.
